ABSTRACT OF THE DISCLOSURE

A machine for indicating and storing the sum of a plurality of data when the data itself is determined by mechanically performing an arithmetic equation physically determined by indicia in each of a plurality of tabulating type cards.

BACKGROUND OF THE INVENTION

This invention is an improvement in the art of arithmetic composing machines and in particular to simple mechanical multipliers having a range of product outputs when the multiplying function is determined by indicia in a tabulating type card.

It is known that the same result can be achieved with existing computers but the present invention is a far simpler solution to the problem.

SUMMARY OF THE INVENTION

A deck of tabulating type cards are provided in which unique to each card separate indicia is provided for each of two elements of an arithmetic equation. A card carriage is provided to support the cards one at a time and to transport them from an inactive position (for insertion) to an active position (for reading). A first mechanical arithmetic device is provided which has selectively one of a range of ratios of output. The particular ratio is selected by sensing one of the indicia in the card as it is moved into its active position. A second arithmetic device is operatively connected to the first device to drive the same. The degree of drive is responsive to an input selected from the second indicia on the card.

DESCRIPTION OF THE DRAWINGS

FIG. 1 is a schematic view of the mechanism, shown in perspective, as it is related to one column of a punched tabulating card.

FIG. 2 is a section view of a portion of the multiplier unit.

FIG. 3 is an exploded view—in perspective—of a friction disc and support.

FIG. 4 is a plan view showing two tabulating cards.

DESCRIPTION OF THE PREFERRED EMBODIMENT

Referring now to the drawings a composing mechanism comprises a cog belt 2 having preferably a decorated (colored) outer surface 4 and an inner surface providing cog teeth 5 in the form of a flexible rack 6. The belt 2 is mounted for guided movement relative to an indicating scale 8 to indicate values.

Belt 2 is mounted for engagement with a sprocket 10 which is fixed for coaxial angular movement with a face gear 12. The face gear 12 and sprocket 10 are freely rotatable as a unit about a shaft 14 which merely supports them for rotation. The face gear 12 engages a pinion 16 which is positively connected to a shaft 18 which carries at its opposite end a roller 20. Roller 20 has a central aperture or keyway which is axially movable along splines 22 carried by shaft 18. Roller 20 preferably carries a rubber rim 24.

2

Multiplier unit

A mechanism is provided for axially moving roller 20 along the splines 22 of shaft 18. This mechanism comprises a carriage 28 which is supported for axial movement on a square or splined shaft 30. The carriage 28 has fingers 29 for guiding and positioning roller 20 along the splines 22 of shaft 18. Once positioned by the fingers 29, roller 20 can rotate freely relative to the fingers.

Carriage 28 is provided with a sensing finger or probe 32 which as shown in FIG. 1 is engageable with a hole 34 punched in a tabulating card 36. In its normal or rest position carriage 28 is pulled by spring 38 back against a stop 40. It should be noted that the square shaft or spline 30 is mounted for pivotal motion about its own axis in response to the movement of a crank arm 42, which is mounted for engagement with a cam 44. Cam 44 is mounted to be rocked through an arc from a release position, downwardly to an engaged position. It follows that by rocking the cam 44 from its release position as shown in FIG. 1 to the engaged position the cam will rotate the crank arm 42 to pivot shaft 30 about its axis and consequently rotate carriage 28 counterclockwise as viewed from the crank arm 42 end of shaft 30. It is significant to recognize that carriage 28 is normally biased clockwise by spring 43 to urge roller 20 into engagement with a friction disc 46.

Actually the carriage fingers 29 as shown in FIG. 2 provide bearings 48 for housing stub shafts 50 of roller 20 for rotation. Roller 20 is freely rotatable in the bearings 48 of fingers 29 while being directly connected by means of spline 22 to the shaft 18. When carriage 28 is rotated to its counterclockwise position (as viewed from crank 42 end of shaft 30) roller 20 is disengaged from the friction disc 46 and therefore carriage 28 is freely movable along shaft 30 to carry roller 20 along spline 22. This freedom of motion permits the carriage 28 to be moved axially of shaft 30 in response to the engagement of sensing probe 32 with a hole 34 in the tabulating card 36. Carriage 28 normally is biased to a rest position against stop 40. A tabulating card carriage 37 is provided to support card 36 and to transport it from an inactive to the active position shown in FIG. 1. Carriage 37 is provided with a probe slot 39, permitting probe 32 to sense a hole 34 in card 36. It follows that during movement of the card carriage 37 towards the active position shown in FIG. 1, probe 32 enters hole 34, whereupon further advancement of the card carriage drives carriage 28 away from its stop 40. These parts actually form the multiplier unit and the interrelationship of these parts is prearranged to provide a selected ratio of multiplication, i.e., the axial rotation of the roller 20 relative to the angular rotation of the friction disc 46 increases with the displacement of the roller 20 from the center of the friction disc 46. This displacement in turn is controlled by the interengagement of tabulating card hole 34 and sensing probe 32.

Multiplicand unit

Once the multiplier function has been set then the multiplicand input is added to the mechanism. The multiplicand input controls the angular rotation of the friction disc 46.

It is apparent that for some sets of circumstances there must be a zero multiplication factor and therefore the roller 20 must be engageable exactly at the center of the friction disc 46. It follows therefore that friction disc 46 cannot be centrally or axially supported—particularly if both sides of the friction disc are to be employed for multiplication units.

To effect this relationship between friction disc 46 and roller 20 and yet support friction disc 46 for angular motion the following mechanism is provided (FIG. 3). The

friction disc 46 has little axial length. Actually it comprises a circular plastic disc 52 having circular discs of sandpaper 54 cemented to each lateral surface. The periphery of disc 52 is equipped with gear teeth 56. The disc 46 is supported for rotation in a plate 58 which has an aperture 59 slightly larger than the outside diameter of the gear teeth 56. The disc 46 is limited in axial movement by two plates 62-64 which are connected to plate 58 to sandwich the disc 46 between them. Furthermore, each plate 62-64 carries a slot 66 to expose a portion of the abrasive surface 54. The slot 66 exposes a diametrical section of disc 46 and it is large enough to permit roller 20 to extend through it to engage the surface 54 and long enough to permit roller 20 to be moved with carriage 28 and engage disc 54 at any selected ratio position.

Plate 58 is provided with a clearance opening 65 and side plates 62-64 are provided with bearing 66 to support a necked pinion 68 for free rotation relative to the plates. The pinion 68 is mounted for engagement with the teeth 56 of disc 46 (FIG. 1). Pinion 68 is equipped with a square or splined center 70 through which a square or splined shaft 72 is passed to drive the pinion, i.e., as shaft 72 is rotated, pinion 68 rotates to drive gear teeth 56. The square shaft 72 carries at one end a pinion 74 which is also fixed for rotation with the shaft 72. Pinion 74 is mounted for engagement with a thumb wheel 76 which includes gear teeth for driving pinion 74. It follows that rotation of the thumb wheel acting through pinion 74, shaft 72, pinion 68 will drive the friction disc 46 through some angular motion.

Provision must now be made for indicating the amount of rotation of the thumb wheel from a home position to a measured position depending upon the number of units of input that are selected. To accomplish this, a pinion 78 is supported on the shaft 72 in engagement with an idler gear 80 which in turn is supported on a crank arm 82 which in turn is mounted for pivotal movement about the shaft 72. In one of its positions the gear 80 drives a pinion 84 supported for rotation with a shaft 86. It is significant at this point to note that the crank arm 82 is normally biased out of engagement with the pinion 84 by means of a spring 88. A mechanism is provided, however, for advancing the crank arm to mesh the gear 80 with pinion 84. Specifically, the mesh takes place when the card carriage is moved to its operating position. This not shown but any simple mechanical mechanism operative as the carriage is moved from a rest to an operating position will suffice. Actually the carriage may simply push the crank arm 82 into engagement with the pinion 84.

Shaft 86 carries a helical groove 90 which engages a follower 92 that carries an indicating pointer 94. Follower 92 is restrained from rotary motion but moves axially in response to the rotation of shaft 86 to carry the pointer 94 along a predetermined path. A torsion spring 96 is connected to shaft 84 tending to bias the same to a rest or inoperative position wherein carrier 92 is against the stop 98. It follows that when crank arm 82 is rotated to release gear 80 from mesh with pinion 84 the torsion spring 96 operates to unwind shaft 86 and thereby drive carrier 92 up against stop 98.

The multiplicand scale is shown on the tabulating card itself. Actually the length of each multiplicand scale is identical but the length is subdivided into units that are substantially unique to each card for the simple purpose of providing practical ranges: e.g. one card may have as its multiplicand scale slices of pie measured in $\frac{1}{8}$ of a pie, while another may have as its multiplicand scale pats of butter. There need not be any correlation between the scales of any two cards, but it must be remembered that the card itself is a functioning part of the mechanism—i.e., it physically determines the multiplier ratio and then provides the scale for setting the selected multiplicand.

For practical comprehension of this invention, reference is made to the composing by adding the arithmetic products of the component content of a number of foods which arithmetic product is produced by multiplying the number

of portion sizes of a food by the number of units of a food component in a portion size.

In the operation of the mechanism described, a person first selects a card representing the food he wishes to use. The card is placed on the card carriage 37 which is then moved from its rest to its operative position shown in FIG. 1. In so doing the probe 32 will sense the hole 34 in the card 36 and advance the carriage 28 to a position which is responsive to the location of the hole 34 in the card. The carriage 28 is then released so the wheel 20 engages the friction disc 46 through the aperture 66 in plate 62. The multiplier ratio for that ingredient of the selected food is then set. It will be noted again that while the mechanism has been described for only one ingredient of a selected food, actually the mechanism is repeated for each measured ingredient of the food, but while each ingredient may set up a different ratio in its respective multiplier systems, the units of measure in the multiplicand system are common to them all.

Once the multiplication factor has been set as described in the above paragraphs the thumb wheel 76 is turned to advance the quantity indicator pointer 94 to the number of ounces or grams of the food intended to be recorded. The movement of the thumb wheel acting through the pinion 74 and shaft 72 drives the pinion 68 and through teeth 56 the disc 46. The wheel 20 rotates in response to the angular motion of disc 46 to drive shaft 18 which through pinion 16 drives the face gear 12 and accordingly pinion 10 through some angular motion. Pinion 10 drives the output belt 2 along the scale 8 so that the outer surface 4 of the belt will indicate the number of units of the selected ingredient of the food represented by card 36.

It is important to note that, after the information in card 36 has been recorded, the release of card carriage 37 releases crank arm 82 to permit shaft 86 to spin free thereby returning follower 92 to its home position against stop 98. However the information from card 36 remains in the indicating mechanism including scale 8. Then when a second card 36a is inserted in to the machine, the information in card 36a is added to the information already stored through card 36.

It is thought that the invention and many of its attendant advantages will be understood from the foregoing description and it will be apparent that various changes may be made in the form construction and arrangement of the parts without departing from the spirit and scope of the invention or sacrificing all its material advantages, the form hereinbefore described being merely a preferred embodiment thereof.

I claim:

1. A multiplying device comprising in combination a mechanical multiplier having means responsive to being driven through units of input for generating selectively in response thereto one of a range of outputs, a plurality of tabulating type cards each having unique multiplier ratio indicia and a graduated scale representing units of multiplicand input, a card carriage for supporting said cards one at a time, means mounting said carriage for movement at will between an inactive and an active position, a device for sensing the multiplier ratio indicia in a card mounted on said carriage, means interconnecting said sensing device with said carriage and said multiplier unit for selecting the output of said multiplier in response to the sensing of said multiplier ratio indicia as said card carriage is moved from its inactive to its active position,
2. A multiplicand device having an indicator movable across the multiplicand scale of a card mounted on said carriage when said card carriage is in its active position, and means interconnecting the multiplicand device with said multiplier for driving the latter through the multiples of units of input indicated on said multiplicand scale.

2. The mechanism of claim 1 in combination with an indicating scale, an indicator associated therewith and movable relative thereto, and means interconnecting said multiplier output with said indicator for advancing said indicator to an indicating position on said scale to record and store a value representative of the multiplier output.

3. The mechanism of claim 2 wherein said indicator is a tape in the form of a flexible cog belt and said multiplier output has a gear meshed with the cogs of said belt for driving the same to an indicating position.

4. A composing machine into which a pre-determined number of a group of punched cards may be inserted, one at a time for the purpose of accumulating and indicating arithmetic information, a plurality of cards each having indicia for directing separately each of two elements of an arithmetic equation, a card carriage, including a device for holding said cards one at a time, means for supporting said carriage for movement selectively from an inactive to an active position, an arithmetic mechanism capable when driven of generating a ratio output conditioned by the selection of one of a number of corresponding ratio factors, means conditioned by one of the indicia in said card and responsive to its movement with said carriage from the inactive to the active position for selecting and setting the ratio factor in said arithmetic mechanism, a second mechanism operatively connected to said arithmetic mechanism for driving the same, means proportioning the degree of output of said arithmetic mechanism to the movement of said second mechanism to a setting representative of any one of a number of settings indicated by the other indicia on the same punched card.

5. A composing machine into which a pre-determined number of a group of punched cards are inserted, one at a time, for the purpose of accumulating and indicating arithmetic product information comprising in combination a plurality of tabulating type cards each having unique multiplier ratio indicia and a graduated scale representing units of multiplicand input, a card carriage including a device for holding said cards one at a time, means for supporting said carriage for movement selectively from an inactive to an active position, an arithmetical multiplying mechanism capable when driven of generating a ratio output conditioned by the selection of one of a number of corresponding ratio factors, means conditioned by indicia in a said card and responsive to its movement with said carriage from the inactive to the active position for selecting and setting the ratio factor in said arithmetic multiplying mechanism, a multiplicand mechanism operatively connected to said multiplying mechanism for driving the same as the multiplicand mechanism is moved to a setting representative of any one of a number of multiplicands indicated on the graduated scale of said card carried by said carriage, an indicating scale, an indicator associated therewith and movable relative thereto, and means responsive to the generated product information for advancing said indicator to an indicating position on said scale to record and store the arithmetic product of a multiplier and a multiplicand determined by indicia on said card.

6. The mechanism of claim 5 including means retaining said indicator in the advanced position generated by the indicia in a first card after the latter has been moved with card carriage to its inactive position and then being movable to a second position in response to generated product information from a second card to compose the information from both cards.

7. A composing machine into which a predetermined number of a group of punched cards are inserted, one at a time, for the purpose of accumulating and indicating arithmetic product information comprising in combination a plurality of tabulating type cards each having unique multiplier ratio indicia and a graduated scale representing units of multiplicand input, a card carriage including a device for holding said cards one at a time, means for supporting said carriage for movement selectively from an inactive to an active position, means restricting inser-

tion of a card on said carriage to its inactive position, an arithmetical multiplying mechanism capable when driven of generating product information, means in said arithmetic multiplying mechanism for varying the ratio of product output in response to the selection one at a time of one of a plurality of correlated ratio factors, means conditioned by multiplier ratio indicia in said punched card and responsive to its movement with said carriage from the inactive to the active position for selecting and setting the ratio factor in said multiplying mechanism, a multiplicand mechanism operatively connected to said multiplying mechanism for driving the same, means proportioning the degree of product output to the movement of the multiplicand to a setting representative of any one of a number of multiplicands indicated on said punched card, an indicating scale, an indicator associated therewith and movable relative thereto, and means responsive to this product generated information for advancing said indicator to an indicating position on said scale to record and store the arithmetic product information.

8. A composing machine into which a predetermined number of a group of cards are inserted, one at a time for the purpose of accumulating and indicating arithmetic information comprising in combination a plurality of cards each having first and second indicia for directing separately each of two elements of an arithmetic equation, a card carriage including a device for holding said cards one at a time, means for supporting said carriage for movement selectively from an inactive to an active position, a first arithmetic mechanism capable when driven of generating an output conditioned by the selection of any one of a range of ratio factors, means conditioned by first indicia in said card and responsive to its movement with said carriage from the inactive to the active position for selecting and setting the ratio factor in said first arithmetic mechanism, a second arithmetic mechanism operatively connected to said first arithmetic mechanism, and means proportioning the degree of output of said first arithmetic mechanism to a setting of said second one representative of second indicia in said card, an indicating scale, an indicator associated therewith and movable relative thereto, and means responsive to the output of the first arithmetic mechanism for advancing said indicator to an indicating position.

9. A composing machine into which a predetermined number of a group of punched cards are inserted, one at a time for the purpose of accumulating and indicating arithmetic product information comprising in combination a plurality of tabulating type cards each having unique multiplier ratio indicia and a graduated scale representing units of multiplicand input, a card carriage including a device for holding said punched cards one at a time, means for supporting said carriage for movement selectively from an inactive to an active position including a device for releasably detaining said carriage in either of said positions, a mechanical arithmetic multiplying mechanism capable when driven of generating product information, adjustable means for varying the rate of multiplication of said multiplying mechanism through a predetermined range to generate a product output, means conditioned by multiplier ratio indicia in said card and responsive to its movement with said carriage from the inactive to the active position for selecting and setting the ratio factor in said multiplying mechanism, a multiplicand mechanism operatively connected to said multiplying mechanism for driving the same, means proportioning the degree of product output to the movement of the multiplicand to a setting representative of any one of a number of units of multiplicand input indicated on the same card, an indicating scale, an indicator associated therewith and movable relative thereto, and means responsive to the product output for advancing said indicator to an indicating position on said scale to record and store the arithmetic information product of a multiplier and a multiplicand determined by indicia on said card, means

retaining said indicator in advanced position generated by the indicia in a first card after the latter has been moved with card carriage to its inactive position with said indicator then being movable to a second position in response to product output from a second card to compose the information from both cards.

10. A composing machine into which a predetermined number of a group of punched cards are inserted, one at a time for the purpose of accumulating and indicating arithmetic product information responsive to conditioned indicia contained in said cards comprising in combination a plurality of tabulating type cards each having unique multiplier ratio indicia and a graduated scale representing units of multiplicand input, a card carriage including a device for holding said cards one at a time, means for supporting said carriage for movement selectively from an inactive to an active position, a mechanical arithmetic multiplying mechanism capable when driven of generating product information, adjustable means for varying the rate of multiplication of said multiplying mechanism through a predetermined range to generate a product output, means conditioned by multiplier ratio indicia in a card and responsive to its movement with said carriage from the inactive to the active position for selecting and setting the ratio factor in said arithmetic multiplying

5 mechanism, a multiplicand mechanism operatively connected to said multiplying mechanism for driving the same, means proportioning the degree of product output of said multiplier mechanism to the movement of the multiplicand to a setting representative of any one of a number of multiplicands indicated on the same card supported by said carriage, an indicating scale, an indicating tape movable relative to the scale, and positive drive means including cogs in the tape itself responsive to the product output of said multiplying unit for advancing said tape to an indicating position.

10 11. The mechanism of claim 10 including means retaining said indicating tape in its advanced position while said first card is removed from the mechanism while 15 permitting said product generated information from a second card to advance said indicating tape to a new position to compose the information from both cards.
